UNITED STATES PATENT OFFICE.

HAMILTON LINDSAY, OF CLEVELAND, OHIO, ASSIGNOR TO THE LINDSAY WIRE
WEAVING COMPANY, A CORPORATION OF OHIO.

METHOD AND APPARATUS FOR WEAVING WIRE CLOTH.

Application filed December 15, 1921. Serial No. 522,483.

This invention relates to weaving wire cloth and is particularly concerned with a method and apparatus for securing an even weave to the finished material.

5 In looms of the fly-shuttle type, when the bobbin is non-rotatably mounted in the shuttle, the "shoot" wire or lay thread has a tendency to twist or "kink" while it is being laid in the shed. The ordinary tensioning devices which are employed to hold the wire taut after the shuttle has come to a stop are only designed to hold the wire comparatively straight until the batten forces it against the previously woven cloth. Consequently, the cloth may be woven with the lay wire having a slight twist or kink at various intervals. This causes the woven cloth to have slight irregularities which are detrimental when, for instance, a belt of such cloth is used in paper manufacturing machines. To reduce this disadvantage it has been customary to employ considerable time for inspection by skilled workers who attempt to remedy the defects by manually smoothing the cloth.

In order, therefore, to overcome the difficulties above set forth, my invention is directed toward the provision of means for stretching each lay thread just before the batten forces it into the woven material, to remove the slight twists or kinks, which may be left in the wire after it has been payed out from the bobbin.

Still another object is to accomplish this result with simple mechanism which may be readily installed on existing looms, and which positively stretches each lay thread before the batten starts on its forward stroke.

40 In accomplishing the above objects, I stretch the shoot wire or lay thread preferably by preventing the thread from uncoiling during a certain interval in the movement of the shuttle and by employing the momentum of the shuttle for stretching the wire by giving it a slight jerk just before the shuttle comes to a stop. In this way, the tendency to twist is taken out of the wire so that a tensioning mechanism which functions after the shuttle has come to a stop, may draw the wire taut and thus hold it comparatively straight until the batten moves forwardly to drive the wire into the woven cloth.

55 The means for carrying out my invention

will be hereinafter fully set forth in the following description, which relates to the drawings, and the essential characteristics of my invention will be summarized in the claims.

60 In the drawing, Fig. 1 is a plan view of the shuttle within a shuttle box, the box being equipped with a wire stretching means constructed according to my invention; Fig. 2 is a section taken through the shuttle box 65 showing the shuttle in position just as it is leaving the shuttle box shown in Fig. 1; Fig. 3 is a section taken through the forward end of the shuttle shown in Fig. 2, and showing the tensioning means in active 70 position; Figs. 4 and 5 are transverse sections taken on the lines 4-4 and 5-5 respectively; and Fig. 6 is a section taken longitudinally in a vertical plane through the shuttle, and illustrating the action of 75 my locking device.

Designating the parts shown in the drawing by the use of reference characters, 10 represents the bottom, and 11 and 12 the side walls of a shuttle box, which is mounted 80 on one side of the loom frame indicated generally at 13. At one end of the shuttle box, I have shown a picker block 14 which is engaged by a picker staff 15, and is adapted to throw the shuttle at predetermined intervals across the loom to the shuttle box on the opposite side of the frame. The shuttle proper comprises a member having side bars 20 and 21 which are connected at the ends 22 and 23, and which are provided 85 with cross bars 24 and 25 adjacent the ends; thus providing an open space for receiving the bobbin 26. The wire which forms the lay thread is previously wound on the bobbin and is allowed to pass through the guides 90 27 to insure the even removal from the bobbin while the shuttle passes from one box to another. At each end of the shuttle are shown rollers 28 and 29.

95 When wire is payed out through a shuttle 100 constructed in accordance with the manner described, there is a tendency for it to twist and curl after it is laid in the shed. Ordinarily the mechanism employed for straightening the thread just prior to the 105 operation of the batten is sufficient to straighten it, but not to take the tendency to twist out of the wire. Accordingly, to remove these kinks, I prefer to employ the momentum of the shuttle for stretching the 110

wire a slight amount. The amount of elongation contemplated, however, is not sufficient to stretch the wire beyond the elastic limit but only enough to take the tendency 5 to twist out of it, so that the subsequently operating tension mechanism may straighten the wire, and hold it until the batten forces it into the woven cloth.

To utilize the momentum of the shuttle for 10 stretching the wire, I provide a mechanism which engages it adjacent the bobbin and positively locks it, thereby preventing it from being payed out, whereupon continued movement of the shuttle stretches the shoot 15 wire just laid. This mechanism comprises a lock and is shown as comprising a member 30 which is free to move laterally through an opening in the side bar 20, and which is adapted to be normally held away 20 from the wire, by means of a leaf spring 31, which is secured at 32 to the inner portion of the shuttle.

Referring now to Fig. 6, I have shown the relative position of the member 30 to the 25 wire as it is being paid out from the bobbin during the locking operation. From this drawing, it will be apparent that the wire 36 passes over the top of the member 30, then between the guides 27 from whence it 30 leads out into the shed. The lock is actuated whenever the member 30 engages a cam 34; there being one of such cams disposed in the path of the member 30 and on each side of the shuttle frame. For convenience, I have 35 shown these cams as mounted within the shuttle boxes, and as so positioned therein, that the lock is released before the shuttle is brought to a stop. For enabling the member 30 to easily engage the cam, I have 40 shown the bearing surfaces thereof bevelled, as at 33, and I have shown the ends of the cam as being similarly shaped.

The position of the member 30, when the lock is applied, is shown in Fig. 3, wherein 45 the wire 36 is locked against the end of the bobbin by the top of member 30. The locking action of the wire is effected by reason of the fact, that the wire is revolving around the bobbin as it is being paid out during 50 the movement of the shuttle, and further, by reason of the fact that the member 30 is normally out of the path of the revolving wire, but is interposed into such path when the bearing surface 33 engages the cam 34. 55 By interposing the member 30 into the path of the wire, then the wire is prevented from revolving further, and as a result, the wire is positively locked and is given a quick jerk while the shuttle is in motion. This jerk 60 stretches the wire in a certain degree. The amount of such elongation is, of course, dependent upon the length of the cam 34, and the effectiveness of such stretching is determined by the relative position of the cam 65 to the shuttle, when it is brought to a stop.

In this connection, satisfactory results are secured when the cam is so positioned that the lock is released before the shuttle is brought to a stop. In this way the reaction of the wire, after being stretched, may be 70 taken care of by allowing a short length of material to be payed out from the bobbin.

While I have illustrated a stretching mechanism adapted for power looms, as embodied 75 in a shuttle operated lock, it is understood that the method illustrated is only one of the various means which may be employed, and that broadly, the invention is concerned with the method of weaving cloth. The means illustrated, however, provides the desired results, in that the wire is stretched 80 an amount sufficient to eliminate the kinks, and still to keep it within the elastic limit of the metal.

The operation of a loom having a shuttle 85 equipped with my invention is as follows: Assuming that the shuttle is in position in the shuttle box shown in Fig. 1, then as the picker staff 15 is actuated by mechanism (not shown) to throw the shuttle to the opposite box, wire is payed out from the bobbin 26. Then as the shuttle approaches the opposite box, the beveled edge 33 of the member 30 rides up on the cam 34, whereupon the top of the member 30 is interposed into 90 the path of the thread 36. So long as the member 30 remains in engagement with the cam 34, the wire 36 is prevented from moving off the bobbin. The movement of the shuttle is so rapid, however, that the lay wire 100 is given a slight jerk which is sufficient to remove the small kinks or unevenness in the wire. As the shuttle is moved still further toward the picker block the member 30 is released by reason of the fact that the surfaces 33 clear the cam 34. Then after the shuttle has been brought to a stop, the straightening mechanism is actuated in the usual manner to hold the wire comparatively 105 straight until the batten is brought forwardly. A similar operation occurs when the shuttle is thrown across the loom on the return stroke.

From the foregoing description, it will be seen that my invention provides a means 115 for stretching a lay thread below the elastic limit of the wire to remove the tendency to twist and kink therein, and that the means may be readily attached to existing looms without making material changes in the 120 construction thereof. Furthermore, this mechanism is positive in its operation, is capable of being accurately adjusted to suit the cloth being woven, and is very simple in construction.

Having thus described my invention, I claim:—

1. In a power loom having a shuttle, shuttle boxes, and means for moving the shuttle across the loom from one box to an- 130

other, the method of weaving wire cloth comprising momentarily locking the wire while the shuttle is in motion near the end of its stroke so as to impart a quick jerk to the wire and then releasing the wire before the shuttle is brought to a stop in the shuttle box.

2. In a power loom having a shuttle, shuttle boxes, and means for moving the shuttle across the loom from one shuttle box to another, comprising passing a woof thread between warp threads then locking the woof thread to the shuttle while the shuttle is in motion and when the shuttle is adjacent the end of the loom toward which it is traveling, maintaining the woof thread locked to the shuttle for a sufficient length of time to take out the kinks and to overcome the tendency to twist therein, then releasing the thread before the shuttle is brought to a stop and subsequently forcing it into the work.

3. In a loom for weaving wire cloth, the combination with a frame of shuttle boxes on each side of the frame, a shuttle adapted to pass from one box to another to lay a wire, said shuttle having a bobbin associated therewith around which the wire revolves while it is being paid out and means for intercepting the wire during the laying operation, said means being arranged to lock the wire upon itself and upon the bobbin while the shuttle is in motion and thereby to stretch the wire sufficiently to remove the kinks therein but to keep the amount of stretching below the elastic limit of the wire.

4. In a power loom, the combination of a

shuttle, a shuttle box therefor, means for moving the shuttle across the loom, a member carried by the shuttle and movable with relation thereto, said member normally allowing the wire to turn around the bobbin while the shuttle is in motion, and means associated with the shuttle box and for interposing the member in the path of the wire, so as to lock the wire to the shuttle positively while the shuttle is in motion, whereby a jerk is imparted to the wire, said last mentioned means being arranged to release said member before the shuttle is brought to a stop.

5. In a power loom, the combination with a shuttle of a bobbin carried thereby, said shuttle having an opening in a side wall thereof, a member carried by the shuttle, said member being mounted inside the shuttle and having a portion thereof normally projecting through the opening and beyond the outer side of the shuttle, a shuttle box for receiving said shuttle, a cam carried by said box and arranged to engage said outwardly projecting portion of the member and to force the member inwardly with relation to the shuttle, said member being forward of the bobbin and spaced therefrom, whereby the wire which is being paid out from the bobbin is caused to engage the top of said member and thereby to be positively locked against further paying out, and whereby a jerk is imparted to the wire, said cam being arranged to release the member before the shuttle is brought to a stop.

In testimony whereof, I hereunto affix my signature.

HAMILTON LINDSAY.
